WITNESS

Arthur Iwan

INVENTOR

Paul Iwan.

UNITED STATES PATENT OFFICE

PAUL IWAN, OF CHICAGO, ILLINOIS

KNITTED CAP

Application filed February 16, 1929. Serial No. 340,515.

This invention pertains to knitted caps and the object of my invention is to provide a knitted cap, containing therein a degree of comfort and protection to the ears hitherto not achieved. A further object is to provide a cap of attractive appearance and symmetrical lines.

In knitted caps commonly used today, the method employed to achieve protection for the ears, is to provide a varying degree of tension in the cap, thereby causing it to conform to the irregular outlines of the head, jaws, and neck, thus preventing cold from entering below the cap. This necessarily causes more or less pressure on the head, particularly on the ears, forcing them out of position, and is undoubtedly uncomfortable in a varying degree, in some cases necessitating frequent removal of the cap to relax the ears. Such caps also after frequent wearing become loose at their bottom, allowing cold to enter there. How my cap overcomes these faults I will explain in connection with the drawings, of which:—

Figure 1 is a plan view showing the strips of knitted fabric from which my cap is formed.

Figure 2 is a bottom view of cap.

Figure 3 is a front view of cap.

Figure 4 is a side view of my cap on the head.

My cap consists of zig-zag or also called diagonally related knitting, Fig. 1. This form of knitting I do not claim as new broadly, but I do claim as new the arrangement of such knitting into sections, and the joining of such sections by seams, to form a cap such as I will describe.

I knit a flat strip of diagonally related knitting, one border edge having five angular projecting selvages of equal size and shape, and parallel selvages on the other border edge, the whole representing ten distinct sections of knitting, eight of which are of equal width, enclosed on each end by a section which is a trifle wider, which is cut away in the manner indicated. Fig. 1, 1 and 2.

The projection Fig. 1—3 represents the front center part of cap, and the projections

4 and 5 and 6 and 7 are used to form ear laps. These projections are apparently not of sufficient depth to cover the ears fully, but when the cap is placed on the head, the center of the top of cap assumes a position well to the back of the head, Fig. 4, 8—allowing the ear laps to extend well below the ears.

The projections 4 and 5 on one side of cap and 6 and 7 on the other side are then formed into ear laps by sewing together the selvages Fig. 1, 9 and 10, and also 11 and 12, preferably by a hand seam which is hardly visible; which results in a bulging and fullness of fabric, Fig. 3, 13 and 14, forming ear laps, which exert no pressure on the ears and allow them to remain in their natural projecting position when the cap is worn. This I claim to be new and useful.

The bottom edges of the ear laps by this arrangement are given an inherent tendency to curl inward, Fig. 2, 15 and 16, thereby adjusting themselves to the irregular contour of the cheeks, jaws, and neck, thus surrounding and enclosing the ears and affording a degree of protection hitherto not possible without exerting pressure on the ears. This I also claim as new and useful.

The least amount of elasticity or stretch in the fabric of which my cap is formed is in a direction parallel to the selvages.

The bottom edges of the ear laps, Fig. 2, 17 and 18, being unbroken selvages, and being already stretched in the process of making the ear lap, and containing four less sections of knitting than the balance of the cap allows therefore a very limited stretch insuring thereby a lasting fit at the place where ordinary caps stretch most easily, and where a close fit is most necessary to protect the ears. This I also claim as new and useful.

The top of my cap is made by sewing together the selvages Fig. 1—19 and 20, and also 21 and 22, on one side, and also 25 and 26 and also 27 and 28 on the other side of the cap. Then the strip is folded in the center, and where the selvages 23 and 24 join a seam is begun, joining the selvages 23 and 24 continuing to form a junction with the existing seams Fig. 2—41, and is continued joining the ends of the strip, 29 and 30, completing

the top, which is of round form and conforms closely to the shape of the head, Fig. 4,—the heavy lines denoting the seams. This arrangement of knitting and sewing allows ten 5 sections of diagonally related knitting, each coming to a point—Fig. 1, 31 to 40, inclusive, to meet in a common center at the top of cap Fig. 4, and thereby giving the cap, particularly when different colors of yarn 10 are used in the knitting, an attractive and symmetrical appearance. This I also claim as new and useful.

The whole represents a cap which by conforming closely to the outline of the head 15 and ears, allows a close fit without exerting pressure on any part thereof.

This being a full and complete disclosure, I claim the following:—

1. A knitted cap comprising sections of 20 diagonally related knitting of substantially equal width, the selvages of one border thereof and the end edges being sewed together to form a cap of round shape, and an ear pocket being formed at each side by joining 25 the adjacent edges of two points of the other border selvage.

2. A knitted cap comprising a strip of 30 diagonally related knitting sub-divided into sections of substantially equal width, forming on one border edge thereof angular projecting selvages of equal size and shape and parallel selvages on the opposite border edge, the ends of the strip being cut in a concave 35 manner above the lower border selvage forming a small projection on each end of said border, for shaping the cap to the curve at the back of the neck of the wearer.

3. A knitted cap comprising diagonally related knitting, having angular projections on 40 one border edge thereof, a central projection forming the peak of the cap and two of said projections on each side thereof being formed into a bulging ear pocket by a seam joining their originally divergent adjacent edges.

4. A knitted cap comprising a strip of 45 diagonally related knitting sub-divided into sections of substantially equal width forming on one border edge thereof angular projecting selvages of equal size and shape and 50 parallel selvages on the opposite border edge, an ear pocket being formed at each side by joining the adjacent edges of two of said angular projections of one border providing a localized fullness for the ears without 55 stretching the material at said border while causing the cap to fit snugly below the ears, the ends of the strip being cut in a concave manner above the lower border selvage to 60 form a small projection at each end of said border for shaping the cap to the curve at the back of the neck of the wearer.

PAUL IWAN.
